CLAIM

The ornamental design for an electrode, as shown and described.

DESCRIPTION

FIG. 1 is an isometric view, from the bottom back side, of the electrode.

FIG. 2 is an isometric view, from the upper front side, of the electrode.

FIG. 3 is an elevation view of the back of the electrode.

FIG. 4 is a plan view of the bottom of the electrode.

FIG. 5 is a plan view of the front of the electrode.

FIG. 6 is an elevation view of the top of the electrode.

FIG. 7 is an elevation view of the left of the electrode; and,

FIG. 8 is an elevation view of the right of the electrode.
